LOADING CHUTE

Gunnar W. Guhlin and Travis G. Waggoner,
Houston, Tex.

Application July 23, 1938, Serial No. 220,839

12 Claims. (Cl. 214—15)

This invention relates to a loading chute.

An object of the invention is to provide a chute of the character described specially designed to be mounted in the hatch of a ship for loading loose material such as scrap iron or other similar material.

It is another object of the invention to provide a chute of the character described which may be moved longitudinally, as well as transversely, of the hatch and which may be swung around about a vertical axis so as to deliver the freight or merchandise at the desired location.

It is a further object of the invention to provide apparatus of the character described whereby the chute proper may be elevated or lowered.

It is a further object of the invention to provide in apparatus of the character described a chute having an adjustable discharge end for controlling the discharge, therefrom, of the freight delivered along the chute into the vessel.

With the above and other objects in view, the invention has particular relation to certain novel features of construction, operation and arrangement of parts, an example of which is given in this specification and illustrated in the accompanying drawings, wherein:

Figure 1 shows a side elevation of the apparatus.

Figure 2 shows a rear view of the chute proper.

Figure 3 shows a plan view, partly broken away.

Figure 4 shows a cross-sectional view taken on the line 4—4 of Figure 3.

Figure 5 shows a side view of the chute-adjusting mechanism.

Figure 6 shows a rear elevation thereof.

Figure 7 shows a fragmentary, edge view of the chute locked or secured in its lower position.

Figure 8 shows a similar view, showing the locking mechanism released for the adjustment of the chute.

Figure 9 shows a fragmentary edge view of the chute locked in elevated position.

Referring now more particularly to the drawings wherein like numerals of reference designate the same parts in each of the figures, the numerals 1, 1 designate parallel tracks arranged on opposite sides of the hatch 2 of the vessel to be loaded. Extending transversely of the hatch and spaced the required distance apart, are the beams 3, 3. These are preferably in the form of I-beams. They are mounted on the rollers 4, 4 which run along the tracks 1. They form a support on which the circular frame 5 is mounted

and to which it is secured in any preferred manner as by welding. A transverse bar 6 extends across the circular frame 5 toward the forward end of the structure. At the opposite side of the frame are the transverse parallel tracks 7, 8 preferably formed of I-beams, the former of which is mounted on the rollers 9, 9 which in turn are supported on the circular frame 5. The bar 6 is anchored to the track 7 by means of the longitudinal end bars 6a, 6a and depending from the respective ends of the bar 6 are the rollers 6b which run on the circular frame 5. The track 8 is supported on a suitable A-frame composed of the side members 10, 10 whose forward ends are attached to the track 7 and which converge rearwardly and whose rear ends are mounted on and secured to the channel 11. This channel is supported by a cross-roller 12 which in turn travels on the circular frame 5 as shown in Figures 1, 3 and 4.

The outer flange of the channel 11 is extended downwardly and mounted thereon is an inside roller 13 which rides against the underside of the top flange of the circular track 5. The inner flange of the channel 11 extends downwardly below the level of the top flange of the circular frame 5, as shown in Figure 4 whereby to prevent displacement of the channel 11 from the circular frame 5. The tracks 7, 8 are thereby anchored together and mounted so that they may rotate as a unit around the circular frame 5 and the entire structure, including the beams 3, may move back and forth along the tracks 1.

As will be noted from an inspection of Figures 1, 3 and 4 the tracks 7, 8 and the side members 10 of the A-frame form a supporting framework for the platform 14. This platform is mounted to move transversely of the circular frame 5, on the tracks 7, 8 and for that purpose is provided with the rollers 15, 16. The platform 14 is provided to support the chute proper 17. The chute is arranged in front of the platform 14 and extends at the desired angle down through the hatch into the vessel. It may be of any selected design. Pivoted to the lower end of the chute there is a transverse, forwardly directed, plate-like deflector 18. The deflector is adjustable so as to determine the direction of the discharge of the freight or other articles passing downwardly along the chute onto the deflector. At the lower end of the chute, on the rear side, are the transverse cleats 19, 19, 19a having aligned bearings therethrough to receive the adjusting rods 20, 20. The lower ends of these rods are forwardly directed and have the upwardly turned fingers 21.

50 55

on which the deflector 18 is supported. Above the upper cleat 19a the rods 20 are formed with the heads 28a which limit the downward movement of the rods 20. Beneath the cleat 19a the rods 20 are connected by a yoke 22 and surrounding said rods 20 and interposed between the yoke 22 and the cleat 19a are the coil springs 23. There are the cables 24, 24 attached at one end to the respective ends of the yoke 22 and at their other ends to the respective ends of the yoke 25 and these cables work around the sheaves 26, 26 mounted on the underside of the chute 17.

Rotatably mounted on the underside of the chute 17 there is a drum 27 which may be rotated by the crank 28. A cable 29 is attached at one end to the yoke 25 and its other end is wound around the drum 27. If it be desired to elevate the deflector 18 the drum 27 may be turned to wind up on the cable 29 and will thereby move the rods 20 and fingers 21 upwardly to increase the upward inclination of said deflector. The spring 23 will yieldably maintain the yoke 22 and the transverse cleat 19a in spaced relation so that the cable 29 is always tight. The drum 27 may be held against reverse turning by means of a conventional rack-and-dog arrangement 30.

Underneath the platform 14 and mounted to rotate in suitable bearings depending from said platform there is a shaft 31 which has a drum 32 loosely mounted thereon and arranged to be clutched and declutched from the shaft by means of a jaw clutch 33 which is splined on the shaft 31. There is a cable 34 which is wound around the drum 32 and whose opposite ends are attached to the anchors 35 on the track 7. The platform 14 and the shaft, and shaft adjusting mechanism on said platform may be moved along the tracks 7, 8 by rotating the drum 32 one way or the other as desired. The rear end of the shaft 31 has a bevel gear wheel 36 fixed thereon which is in mesh with and is driven by a similar bevel gear wheel 37 which is fixed on the lower end of the vertical shaft 38 rotatable in a suitable bearing in the platform. The upper end of the shaft 38 has a bevel gear wheel 39 fixed thereon which is in mesh with and is driven by a corresponding bevel gear 40 on the shaft of the electric motor 41 and through the gearing above described the shaft 31 may be driven. The clutch 33 may be shifted by any conventional type of clutch shifting lever or mechanism.

Upstanding from the platform 14 are the spaced standards 42, 42 and a transverse shaft 43 is mounted to rotate in suitable bearings in these standards. This shaft also rotates in the intermediate bearings 44, 44 in the upstanding bearing supports 45, 45 as shown in Figure 6. The motor shaft is geared to the main counter-shaft 43 by means of the spur 46 which is fixed on the motor shaft and which is in mesh with and drives the spur gear 47 which is fixed on the shaft 43. Loosely mounted in the respective ends of the shaft 43 are the cable winding drums 48, 49 which are arranged to be clutched with and declutched from said shaft by means of the jaw clutches 50, 51 which are splined on the shaft 43 and which may be shifted by any conventional type of clutch shifting lever.

There are the intermediate cable winding drums 52, 52 loosely mounted on the shaft 43. These drums 52, 52 are formed integrally and may be clutched with and declutched from the shaft 43 by the jaw clutch 53 which may be shifted into and out of clutching relation with the drums by the conventional clutch shifting

lever. The clutches 50, 51 and 53 are suitably splined on the shaft 43. The drums 48 and 49 and one of the drums 52 are each formed with brake flanges as 54, 55 and 56 surrounded by the brake bands 57, 58 and 59 whereby the rotation of the drums may be controlled and whereby the drums may be held against rotation when declutched from the shaft 43.

There are the cables 60, 60 which are attached at one end to the transverse bar 6 and which pass around the sheaves 61 and the rollers 62, on the corresponding sides of the chute 17, and which pass thence over the pulleys 63, 63 mounted on the inner sides of the upper ends of the standards 42 and the other ends of the cables 60 are wound about the respective drums 48, 49. When these last mentioned drums are clutched with the shaft 43 and the motor is started the cables 60 will be wound up and the chute 17 will be thereby bodily elevated. It is preferable to operate the clutches 50, 51 by a common clutch shifting mechanism so that the drums 48, 49 will be simultaneously clutched with and declutched from the shaft 43. When the drums 48, 49 are declutched from said shaft the cables 60 will unwind and allow the chute 17 to descend and the descent of the chute may be controlled by the brakes 57, 58.

Slidably connected with the standards 42 and vertically movable thereon are the supplemental standards 64, 64. Mounted in suitable transversely aligned bearings in the supplemental standard 64 there is a rotatable shaft 65 one end of which has the controlling lever 66 fixed thereto. The supplemental standards 64 are supported in their lower position on the outwardly extended studs 67 which are carried by the standards 42 as shown more clearly in Figure 6.

Fixed to the shaft 65 are the arms 68, 68 whose upper free ends are pivotally connected to the links 69, 69 which may be adjusted in length by conventional turnbuckles 70, 70. The upper ends of these links support a transverse rod 71.

The upper ends of the supplemental standards 64 are connected by a transverse rod 72 and pivotally mounted on this rod 72 are the levers 73, 73 whose lower ends have bearings on the respective ends of the rod 71 as shown in Figures 5 and 6. The upper ends of the levers 73 are forwardly curved and have the inside rollers 74 mounted thereon which overhang the margins of the chute 17 as clearly shown in Figures 7 to 9, inclusive.

Depending from the side margins of the chute 17 are the rack members 75, 75 whose lower margins are serrated forming series of transversely aligned seats 76 between the teeth thereof.

The levers 73 have the inwardly projecting studs 77 on their inner sides which normally engage in the corresponding seats 76, as shown in Figures 7 and 9 to hold the chute 17 in a selected position. The lever 66 may be moved forwardly or into the position shown in Figure 8. This will partly rotate the shaft 65 exerting a downward pull on the links 69 and elevating the rollers 74 clear of the chute 17 as shown in Figure 8 and at the same time the lift arms 78, fixed on the levers 73, will engage underneath the margins of the chute 17 and elevate said chute so as to unseat the seats 76 from the studs 77 and the drums 48, 49 may then be rotated as hereinabove explained to move the chute upwardly or the clutches 50, 51 may be released to permit the chute to move downwardly by gravity, as previ-

ously explained, and when the desired adjustment of the chute has been accomplished the lever 66 may be moved back to original position as shown in Figures 7 and 9 so as to seat the studs 77 in the 5 corresponding seats 78 to hold the chute at the desired point of elevation.

If it be desired to change the angle of inclination of the chute 7 this may be done by elevating the supplemental standards 64 as shown in Figure 10 9. For this purpose the cables 79, 79 have been provided. These cables are attached at one end to the shaft 65 and each cable passes over the pulleys 80, 81 rotatably mounted on the cross-bar 82 whose ends are connected to the standards 42 15 and the other ends of these respective cables 79 are wound around the corresponding drums 52, 52. The clutch 53 may be engaged with said drums 52 and upon rotation of the drums 52 the cables 79 will be wound thereon and the supplemental 20 standards 64, 64 and the appendants thereon will be elevated thus elevating the upper end of the chute 17 and changing the pitch of the chute. The supplemental standards may be held at any desired point of elevation by means of 25 the brake 59 and upon release of said brake the supplemental standards 64, 64 the appendants thereon and the upper end of the chute will be lowered by gravity.

The drawings and description disclose what is 30 now considered to be a preferred form of invention by way of illustration only, while the broad principle of the invention will be defined by the appended claims.

What we claim is:

35 1. A loading chute shaped to be located in the hatch of a vessel, a carriage supported on and movable along the sides of the hatch, a frame forming a circular track on the carriage, a trans- 40 verse track on the frame and movable about a vertical axis around the frame, means movable along the transverse track and supporting the chute.

45 2. A loading chute shaped to be located in the hatch of a vessel, a carriage supported on and movable along the sides of the hatch, a frame forming a circular track on the carriage, a trans- 50 verse track on the frame and movable, about a vertical axis around the frame, means movable along the transverse track and supporting the chute, and means for elevating and lowering the chute on said supporting means.

55 3. A loading chute shaped to be located in the hatch of a vessel, a carriage supported on and movable along the sides of the hatch, a frame forming a circular track on the carriage, a trans- 60 verse track on the frame and movable about a vertical axis around the frame, means movable along the transverse track and supporting the chute, and means for varying the angle of inclina- 65 tion of the chute.

65 4. A loading chute shaped to be located in the hatch of a vessel, a carriage supported on and movable along the sides of the hatch, a frame forming a circular track on the carriage, a trans- 70 verse track on the frame and movable, about a vertical axis around the frame, means movable along the transverse track and supporting the chute, means for elevating and lowering the chute on said chute-supporting means, and means for varying the inclination of the chute.

75 5. A loading chute shaped to be located in the hatch of a vessel, a carriage supported on, and movable along the sides of the hatch, a circular track on the carriage, a transverse track on said circular track and movable around the circular

track, means movable along the transverse track and supporting the chute, means for elevating and lowering the chute on said chute-supporting means, and means for varying the inclination of the chute.

5

6. Apparatus of the character described comprising a carriage, a circular track on the carriage, a transverse track movable about a vertical axis on the circular track, a platform movable along the transverse track, supporting standards 10 on the platform, a declining chute extended through the circular track and supported by said standards, means for elevating and lowering the chute relative to the platform and standards, and means for maintaining the chute at a 15 selected elevation.

7. Apparatus of the character described comprising a carriage, a circular track on the carriage, a transverse track movable about a vertical axis on the circular track, a platform movable along the transverse track, supporting standards 20 on the platform, a declining chute extended through the circular track and supported by said standards, means for elevating and lowering the chute relative to the platform and standards, 25 means for maintaining the chute at a selected elevation, and means for varying the inclination of the chute.

8. A loading mechanism comprising a circular frame adapted to be supported by the sides of 30 a hatch of a boat, a transverse track spanning the frame and movably supported thereon, a cargo handling device, means for supporting the cargo handling device movably along the trans- 35 verse track, the path of the cargo handling device being arcuate upon movement of the trans- verse track around the circular frame.

9. A cargo loading mechanism comprising a circular frame adapted to be supported by the sides of a boat hatch, a transverse track spanning 40 the frame, means for movably mounting the ends of the track on the frame, said track being movable about the frame as a chord of the circular track, a cargo handling device, means for mounting the cargo handling device movably along the 45 transverse track.

10. Apparatus of the character described comprising a carriage, a circular track on the carriage, a transverse track movable about a vertical axis on the circular track, a platform movable along the transverse track, supporting standards 50 on the platform, a declining chute extended through the circular track, members on the chute and standards adapted to engage to thereby provide a connection between the standards and the upper end of the chute, means adapted to raise the chute relative to the standards to disengage said members in order to allow longitudinal movement of the chute, and means for suspending 55 the lower end of the chute from the plat- 60 form.

11. Apparatus of the character described comprising a carriage, a circular track on the carriage, a transverse track movable about a vertical axis on the circular track, a platform movable along the transverse track, supporting standards 65 on the platform, a declining chute extended through the circular track and supported by said standards, means for elevating and lowering the chute relative to the platform and standards, 70 means for maintaining the chute at a selected elevation, a deflector mounted on the lower end of the chute, and means under the control of an operator for varying the angle of the deflector relative to the chute.

75

12. A loading mechanism comprising an inclined chute, standards for supporting the upper end of the chute, members on the chute and standards adapted to engage to thereby provide a connection between the standards and the upper end of the chute, means adapted to raise the

chute relative to the standards to disengage said members in order to allow longitudinal movement of the chute, and means for supporting the lower end of the chute.

GUNNAR W. GUHLIN. 5
